UNITED STATES PATENT OFFICE

SAMUEL S. MATTHES, OF MANSFIELD, OHIO, ASSIGNOR TO THE OHIO BRASS COMPANY,
OF MANSFIELD, OHIO, A CORPORATION OF NEW JERSEY

STRAIN INSULATOR

Application filed March 18, 1927. Serial No. 176,352.

My invention relates to strain type of insulators in which porcelain is preferably used, and in which the insulator is placed under compression rather than tension.

5 It is well known that porcelain is a more or less fragile material, and it is advisable when the porcelain is used under strains to distribute the strain over as large an area as practical, thereby reducing the strain per 10 unit of area of contact between the parts.

In the past, sometimes provision has been made to distribute this strain to a limited degree by the use of a thin sheet of lead between the metal parts and the porcelain, 15 and this is possibly satisfactory under some conditions of insulator design. In other cases practically no provision is made at all for distribution of the strain.

The object of my invention is to employ a 20 porcelain insulating element of approved design, and which is considered a standard on the market at the present day, and I have so arranged the parts through which strain is subjected to the insulator that such strain 25 will be quite uniformly distributed.

My invention resides in the new and novel construction, combination and relation of the various parts hereinafter fully described and shown in the accompanying drawing.

30 In the drawing:

Fig. 1 is a view of one face of my invention comprising two insulating units and one of which is in section.

35 Fig. 2 is a view of another face of the invention shown in Fig. 1 and at 90 degrees from that of Fig. 1 about a longitudinal axis. In this figure one of the insulating elements is shown in section.

40 Fig. 3 is a side view of a shim member which I employ.

Fig. 4 is an end view of Fig. 1.

Fig. 5 is a top view of Figs. 3 and 4.

In the preferred embodiment of my invention I employ two insulating members 1 45 which are provided with transverse passages 2 and 3 at right angles to each other. The bearing surfaces of these passages is made to a radius, as this type of insulator is a standard, and was primarily intended for use with 50 a flexible cable, therefore, the bearing sur-

face is made to conform to the radius of a circle. In this type of insulator the porcelain is placed under compression and the insulator has proved to be a very efficient one, both mechanically and electrically, especially when 55 used with a flexible cable.

In order to adopt the insulator for use with rigid fittings, I provide a means interposed between through bolts 4 and the curved bearing surface of the insulator for distributing the strain between the bolts 4 and the insulator uniformly over not only the surface of the insulator, but the surface of the bolt as far as possible. The entire make-up of the insulator, as shown in Fig. 1, comprises the two insulating members 1, the yoke members 5 and 6 and the link members 7. The yoke members may both be like the member 5, or they may both be like the member 6, the difference being one of choice between an eye and clevis. The yoke and link members are secured in position by means of the through bolts 4 and 8 respectively. The bolts are held in position by means of the spring cotters 9 or by other well known suitable means.

Between the through bolts and the insulator is a shim 10 which is provided with a curved surface 11 adapted to conform reasonably close to a curved surface 12 on the 65 insulator.

The radius of the curved surface 11 can be made exactly that of the radius of the curved surface 12. The radius of the curved surface 11 is preferably made a little larger than that of the radius of the curved surface 12, so that under strain the curved surface will change and conform to the radius of the porcelain.

The shim 10 is provided with a groove 13 90 to receive the through bolts 4 or 8, and the bearing surface 14 of the groove 13 is made slightly concave with respect to the surface of the bolt, so that when the strain is first brought upon the shim it will bear at the extreme points 15. This will permit the surface 14 to assume substantially a straight line under strain as the surface 11 conforms to that of the insulator.

95 This construction also prevents the bend- 100

ing of the bolt as its greatest strain will be one of shearing and at the points where it contacts with the edges 15 of the shim 10. If the surface 14 of the shim was originally 5 made straight or high in the center, the strain would very likely come at the center of the bolt, causing the same to bend, but it will be readily appreciated that with the construction described, the strain on the bolt is substantially one of shearing, and the length of 10 the shim is substantially that of the width of the space between the inner faces of the yoke members and also of the link member 7 when the device is assembled.

15 In Fig. 1, it will be noted that the surface 11 of the shim conforms to the surface of the porcelain and the surface 14 of the shim is slightly concave regarding the bolt, and this construction I find gives ideal conditions as 20 it distributes the strain uniformly over the contact surface of the insulator, and places substantially a shearing strain only upon the bolts 4 and 8. This shearing strain will also be accomplished, of course, if the surface 14 25 of the shim is substantially straight, so that it is not higher at the center than at the ends.

I prefer to make the shim 10 of a yielding material such as a malleable cast iron or forging, copper or of a copper base casting. Of 30 course, aluminum may be used, and likewise lead, zinc or tin, but the lead under the circumstances, I find, to be soft where the strain is substantial, and zinc or tin do not seem to have any advantage over a bronze or brass 35 casting.

It will be appreciated that in place of the link 7, the member 5 or 6 may be substituted, thereby making a single insulator strain device instead of a double.

40 The construction described, especially that of the shim, provides means of getting a maximum strength out of the device, in that the strain is quite uniformly distributed over the bearing surface of the insulator, and the 45 strain upon the bolt is one of shear rather than bend.

The shims 10 are first placed in position before the bolts are positioned, as usually the transverse passages 2 are not large enough 50 to permit the insertion of the shims 10 after the through bolts have been inserted.

55 My invention also has the advantage that the parts can be shipped from the factory in an unassembled condition and assembled in the field into either the single or double form as desired, and without the use of any tools whatsoever, other than possibly a screw driver to open up the ends of the spring cotter 9 slightly.

60 There will be modifications, of course, to my invention, which will suggest themselves to those skilled in the art, therefore, I do not wish to be limited other than by my claims.

I claim:

65 1. An insulator comprising an insulating

element having transverse passages spaced apart and having axes at right angles to each other and also having curved bearing surfaces, bolts passing through the passages and fittings secured to the bolts and so disposed 70 as to subject the insulator to compression and a yielding member interposed between each bolt and the insulator to distribute the strain over the bearing surface of the insulator and having a surface to conform to the bearing 75 surface on the insulator and a surface adjacent the bolt and slightly concave thereto.

2. An insulator comprising an insulating member, and metal fittings secured thereto by transversely disposed bolts whose axes are 80 at right angles to each other, shims interposed between the bolts and the insulating member and of such length as to extend beyond the sides of the insulating member, each shim 85 having a surface to conform to the surface of the insulator which it engages and means at the ends of the shims to engage the bolts.

3. An insulator comprising an insulating member, metallic fittings secured thereto by transversely disposed bolts whose axes are at 90 right angles to each other, shims disposed between the bolts and the insulating member and each of such length as to extend beyond the sides of the insulating member, each shim 95 also having a surface to conform to the bearing surface of the insulator and an oppositely disposed groove having a surface arranged to initially engage its bolt at the ends only of the shim to receive the bolt.

4. An insulator comprising a pair of insulating members spaced apart and each having 100 two transversely disposed passages whose axes are at right angles, yoke shaped fittings secured to each insulating member by means of a bolt extending through that passage which is nearest the other insulating member when fully assembled, a pair of link fittings 105 spaced apart and secured to opposite sides of the insulating members by bolts extending through the passages which are farthest from the other insulating member and thereby interlinking the fittings and bringing a compressive strain upon the insulating members when in use, a yieldable shim interposed between each bolt and the corresponding bearing surface on the insulating member and having a surface adapted to be shaped to the bearing surface on the insulating member when under stress and having a groove to receive the bolt, the surface of the groove arranged to initially engage the respective bolts 115 only at points adjacent to the fittings.

5. The combination of an insulator having a bearing surface, a shim formed of a yieldable metal having a surface to rest against the said bearing surface and to conform to the bearing surface under strain, a groove in the 120 shim, a bolt or pin resting in the groove, the surface of the groove adapted to initially engage the bolt or pin only at the outer ends 125

of the groove and supporting means secured to the bolt or pin.

6. An insulator fitting comprising a yoke shaped member and a substantially straight and transversely positioned bolt connecting the free ends of the yoke and an elongated shim of deformable metal engaging the bolt between the ends of the yoke member, the shim having a groove in which the bolt is positioned, the surface of the groove being concavo-concave to engage the bolt initially at the ends of the shim and a groove transversely disposed to the first groove and having a concavo-convex bearing surface and securing means on the yoke at the closed end thereof.

In testimony whereof I affix my signature.
SAMUEL S. MATTHES.
